E. H. ELLISON.

WINDOW HINGE.

APPLICATION FILED JUNE 30, 1920.

1,368,127.

Patented Feb. 8, 1921.

Fig. 1

Fig. 2

Fig.

A technical line drawing of a mechanical component, likely a bracket or a frame. The drawing shows a rectangular base with a central slot and a rib extending to the right. A circular hole is located on the left side. The drawing is annotated with several numbers: 'Fig. 4' is written above the top edge; '15' is placed near the center of the base; '16' is at the end of the right-hand rib; and '17' is at the bottom left corner of the base. The style is characteristic of early 20th-century engineering blueprints.

UNITED STATES PATENT OFFICE.

EDWARD H. ELLISON, OF JAMESTOWN, NEW YORK, ASSIGNOR TO INTERNATIONAL CASEMENT COMPANY, OF JAMESTOWN, NEW YORK, A CORPORATION.

WINDOW-HINGE.

1,368,127.

Specification of Letters Patent.

Patented Feb. 8, 1921.

Application filed June 30, 1920. Serial No. 392,939.

To all whom it may concern:

Be it known that I, EDWARD H. ELLISON, a citizen of the United States, residing at the city of Jamestown, in the county of 5 Chautauqua and State of New York, have invented certain new and useful Improvements in Window-Hinges, of which the following, taken in connection with the accompanying drawings, is a specification.

- 10 The invention relates to hinges for window sash, and particularly on heavy casement windows to provide for the opening of the same so as to admit to both sides of the sash when in the open position and to hold 15 said sash in the open position at any desired angle, folding into small space alongside the sash when closed; and the invention consists in the novel features and combinations hereinafter set forth and claimed.
- 20 In the drawings, Figure 1 is an elevation of a window frame and sash with the improved hinge thereon in right and left formation at the top and bottom of the same. Fig. 2 is a perspective view of the hinge and 25 portions of the window frame and sash in the open position showing the braced hinge support for the window sash in said open position. Fig. 3 is a similar perspective view showing the sash in the closed position, the open position being shown in dotted outline. Fig. 4 is a detail perspective view 30 of the sash plate with the attaching lugs thereon. Fig. 5 is a plan view of the slotted plate on the window frame before attachment thereto, showing the angular end of 35 said slot which draws and binds the window sash against the frame.

Like characters of reference refer to corresponding parts in the several views.

- 40 The numeral 10 designates the window frame, and the numeral 11 the window sash. The window frame 10 has the plate 12 attached on the ends of the same, having a lengthwise slot 13 therein, a lengthened 45 hinge butt 14 being attached on the lateral sides adjacent the corner near which the plate 12 has been attached.

- A sash plate 15 is attached to the front face of the sash 11 beneath the plate 12 and 50 has the round lug 16 thereon which slidably engages in the slot 13, and the spaced lugs 17 on the front face of the plate 15 to pivotally receive therebetween one end of the link butt or hinge part 18, the other end being pivotally attached to the lug 19 of the

butt 14 by means of the pin 20 to form the hinge knuckle.

It is now apparent that with the top and bottom hinges formed in rights and lefts, the sash 11 can be hinged to the frame 10 with the plates 12 on the top and bottom ends of said frame 10 and the hinge butt parts 14 attached to the rear lateral edge of said frame 10 near the upper and lower corners, and the sash plates 15 attached to 60 the corners of the sash 11 and connected to said butts 14 by the pivotally attached link butts 18, permitting the free swinging of the sash 11 on said hinges, the round lugs 16 sliding backward and forward in the 65 lengthwise slots 13.

It is also apparent that the length of the plates 12 and slots 13 should be proportioned to the length of the link 18 so as to open the sash 11 to any desired degree, and that said 70 link butts 18 will hold the sash 11 in the open position, firmly supporting and bracing the same as against gusts of wind or other strains, the sliding attachment to the window frame 10 permitting free access to 75 both sides of the sash in order to clean the window in said sash; also that said hinge parts close into the flat or non-extending position as shown in Figs. 1 and 3, holding 80 and bracing said window in the closed position as well as being ready for quick opening and bracing in said open position.

The right and left or top and bottom hinges are so shaped as to extend out onto the sash, but not to encroach upon the glass-filled lighting area within said sash. Toward this end, the link butt 18 is made angular in shape so that it lies flat against the sash plate 15 when in the closed position. Said link butt is attached to the butt 14 95 preferably by a strong pintle 20 which is headed at each end, the opposite end of the link butt 18 being attached to the lugs 17 on the sash plate 15 in a similar manner, thereby making it difficult to detach said link butt 100 when the window is in the closed position.

The slot 13 in the plate 12 is shaped with an end 21 which is inclined toward the window frame at the end adjacent the corner so that when the sash is in the closed position, as shown in Fig. 3, the lug 16 will enter said inclined end and bind the window sash 11 firmly against the frame 10, making it as nearly air tight as possible by thus binding 105 at both the top and bottom rear corners of 110

said sash, a bolt or latch at the front edge of said sash holding the same firmly in the tightly closed position and binding the sash 11 onto the frame 10.

- 5 11 onto the frame 10.
- 5 The window frame 10 and sash 11 for heavy casement window work are usually made of metal and hence require very strong supporting hinges and bracing connective link butts 18 to hold the sash in line and
- 10 guide it, the word "bracing" being here used in the sense of holding the heavy angular metallic sash firmly in line while opening and closing the same and to assist in holding the sash at any point in opening or closing
- 15 the same.

I claim as new:

1. A window frame, a window sash fitting in said frame, a plate attached to said window frame adjacent the rear corner thereof
- 20 having a lengthwise slot therein, a sash plate attached to the front of said window sash having a lug adjacent the corner of said sash slidably mountable in said lengthwise slot in said plate, a hinge butt attached
- 25 to said window frame adjacent said corner,

and a link hingingly connecting said butt and sash plate to actuate and brace said sash in opening and closing the same.

2. A window frame, a window sash fitting in said frame, a plate attached to said window frame adjacent the rear corner thereof having a lengthwise slot therein with its adjacent end inclined toward said window frame rear corner, a sash plate attached to the front of said window sash having a lug adjacent the rear corner of said sash slidably mountable in said lengthwise slot in said plate and into said inclined end to bind said window sash against the said window frame, a hinge butt attached to said window frame adjacent said corner, and a link hingingly connecting said butt and sash plate to actuate and brace said sash in opening and closing the same.

In testimony whereof I have affixed my signature in the presence of two witnesses.

EDWARD H. ELLISON.
